UNITED STATES PATENT OFFICE.

WILLIAM Y. FORBES AND WILLIAM H. ROTHWELL, OF LIVERPOOL, ENGLAND.

TYPE-WRITING MACHINE.

971,032.

Specification of Letters Patent. Patented Sept. 27, 1910.

Application filed October 31, 1908. Serial No. 460,554.

To all whom it may concern:

Be it known that we, WILLIAM YUILE FORBES and WILLIAM HASTINGS ROTHWELL, both subjects of the King of Great Britain and Ireland, residing at "Lynwood" Huyton, Liverpool, England, have invented a new and useful Improvement in Type-Writing Machines, of which the following is a specification.

10 This invention has reference to typewriting machines and relates to certain paper feeding motions in connection with the platen roller, namely, a motion whereby the paper is led squarely on to the platen at the first onset: an arrangement of finger pieces for keeping the paper closely against the platen; line spacing motions; a frictional arrangement whereby the platen may be turned independently of its ratchet motion: 15 a date line feed motion whereby headed letter paper may be fed into its position to be dated; a supplementary paper holder for use in connection with loose leaf book-keeping; and motions connected therewith.

20 In the annexed drawings:—Figure 1 is an end view of the platen carriage, showing arrangement of press rollers and line spacing gear. Fig. 2 is a sectional detail showing a frictional connection between the platen 25 roller and its line spacing ratchet wheel. Fig. 3 is a part plan of the platen carriage, showing an arrangement of supplementary paper holder, and Fig. 4 is an end view of the same. Fig. 5 is an end view of the platen 30 carriage, showing a date line feeding device. Fig. 6 is an underside plan, and Fig. 7 is a side view, of mechanism for varying the extent of the travel of the line spacing lever.

The paper is led on to the platen roller 35 by a downward movement upon the feeding plate 76, which allows the edge of the paper to fall into the crevice between the platen 75 and the first feed or pressure roller 77, whereby the paper is fed squarely upon the 40 platen at the first onset. Paper fingers 78, that is fingers for keeping the paper closely against the platen, slide upon a rod 79 and are attached to sliding rods 80, the ends of the latter forming finger pieces 81, by which 45 such paper fingers 78 may be adjusted for any space along the platen roller. The first pressure roller 77 and also the second pressure roller 82 are carried on a bow plate 111.

50 Line spacing rotation is imparted to the platen roller by the line spacing lever 82

carried on the hand end of the hand lever 24, through the cord or wire 84 led along the underside of said hand lever, and pull-rod 85, the latter engaging with a bar 86 connecting the side levers 87 on the carriage 13. 55 Upon the upper end of a rod 88 coupled to one of said side levers is a pawl 89, which engages with the crown-wheel teeth of the ratchet wheel 90 on the axis of the platen. The peripheral teeth of this ratchet wheel 60 engage with the usual detent roller.

The extent of the line spacing may be varied by varying the travel of the line spacing lever 83, by means of the stop piece 128 on the sliding rod 129, this rod being slotted 65 and sliding on the pins 130 in the handle 24. The outward end 131 of the rod 129 is bent to form a finger piece and tooth, the latter being sprung into either of the three notches 132 in the handle 24. The full travel of the 70 line spacing lever 83 produces a three-line space, hence by adjusting the end 131 of the rod 129 into either of the notches 132, a one- 75 two- or three-line space is produced by the travel of the lever 83.

A means whereby the platen roller 75 may be turned independently of the ratchet wheel 90, consists in placing the platen in frictional contact with the ratchet wheel, so that the platen may be put in or out of friction with such ratchet. Such device consists of a coned extension 91 on the ratchet, which is pressed into a corresponding cavity in the platen by the spring 95, the cone 91 being withdrawn from friction with the 80 platen by the lever 92 and finger piece 93, the latter being mounted on the axis of the platen and possessing an eccentric boss 94 which depresses the lever 92.

In order that headed letter paper or the like may be fed into the machine so that the date line of such heading assumes its correct position on the platen automatically, there is employed a toothed sector 96 which is arranged to engage and disengage with a pinion 97 on the axis of the platen. The sector 96 is journaled on the eccentric boss 98 of the lever 99. A forward movement of said lever serves to bring the sector into engagement with the pinion 97, and by that time the tooth 100 on the boss 98 engages the pin 101 on the sector, so that both the lever and sector are then rotated about the pin 102, the sector turning the pinion 97 and also the platen until the latter has rotated suffi- 100 105 110 115

ciently to bring the date line into position, this rotation being adjustably limited by the sector 96 coming in contact with the adjustable stop piece 103. When such date line feed has been accomplished the lever 99 is returned to its first position in relation to the sector, either by hand or by spring, which movement disengages the sector 96 from the pinion 97, through the eccentric 10 boss 98, so that the sector is now free to return to its first position under the influence of a spring.

For the purposes of loose leaf book-keeping and other purposes, provision is made 15 for taking an original copy upon a sheet of paper which is capable of manipulation independently of the sheet to be carboned, which latter is carried on the platen roller. For instance, where it is desired to keep a 20 copy of an invoice and also to save the space which would otherwise be occupied by the customer's name and address, that is, where a copy is to be kept of the contents of a number of invoices, on a single sheet, as for instance for the purposes of a loose-leaf stock 25 book, a paper-holder 104 is arranged in front of the platen, in addition to the rear feed plate at the back of the platen. The paper-holder 104 is preferably of the volute 30 form illustrated. The paper which will form the original of the invoice or similar document is inserted backward into the volute holder 104, while the sheet which is to retain a carbon copy of this and succeeding 35 invoices is entered—together with a carbon sheet—upon the platen in the usual way. To permit of the original being inserted into the volute holder 104, the upper portion 105 thereof, is hinged to the lower 40 portion at 106, so that it may be turned upward, and the scale plate 107 is carried by such part and also the paper fingers 78 and their slide rods 79, 80. A spring 108 serves to keep such hinged part of the holder 45 downward. Finger lift-pieces 127 may be formed on the part 105 of the holder. A sheet having been inserted into the volute holder and another sheet and carbon on the platen, the leading edge of the volute sheet 50 is pressed on the platen by the pressure roller 109 carried on the arm 110, the latter being pivoted and capable of being turned into an upright position when not required.

Having now described our invention, what 55 we claim as new and desire to secure by Letters Patent is:—

1. In a typewriting machine, in combination, paper fingers for keeping the paper close to the platen, a carrier rod adapted to

form a slide for said fingers, rods attached 60 to said fingers and projecting from each side of the typewriting machine, and finger pieces on said projecting rod ends, whereby said paper fingers may be adjusted to any width of paper on the platen, as described. 65

2. In a typewriting machine, the combination with the platen spindle, of a pinion wheel, a toothed sector adapted to engage and disengage with said pinion, a lever pivoted on the platen carriage, a boss on said 70 lever eccentric relatively to said pivot and forming a journal for said sector, whereby as the lever is moved on its pivot the sector is placed in gear with the pinion, a tooth on said boss and a pin on the sector in the 75 path of said tooth, whereby the sector is carried around with the lever when said tooth and pin engage, and an adjustable stop on the platen carriage for limiting the travel of the sector, whereby headed letter paper 80 placed on the platen is fed forward to its date line by a movement of said lever, as described.

3. In a typewriting machine, the combination with mechanism by which headed 85 letter paper placed on the platen is fed forward to its date line by a movement of such mechanism, of means for placing the platen out of friction with the line spacing ratchet, comprising a friction cone on said ratchet, 90 a lever for placing said cone in and out of friction with the platen, and an eccentric finger piece for actuating said lever, whereby the platen is held out of friction with its ratchet while the said date line feeding 95 mechanism is operated as described.

4. In a typewriting machine, the combination with a revoluble platen, a paper table disposed to the rear and inclining forwardly downward to the platen, a supplementary 100 paper holder disposed on the front side of the platen and having its upper portion hinged to its lower portion, a scale bar attached to said upper portion, rods adapted to carry paper fingers also attached to said 105 upper portion of said paper holder, whereby paper sheets intended as original copies may be successively inserted into said holder without disturbing the paper upon the platen which receives carbon copies of said 110 successive originals, substantially as described.
